[57] ABSTRACT

There is provided a process for the upgrading of a malodorous, sulfur-contaminated, aliphatic, aromatic or cycloaliphatic olefinic derivative or mixture thereof which involves contacting said malodorous, sulfur-contaminated derivative or mixture thereof with from 1 to 2 equivalents of a per(lower)alkanoic acid per mole of sulfur in said olefinic derivative, the amount of said acid being sufficient to oxidize the sulfur content therein, maintaining the treated solution at a temperature ranging from about -10°C. to about 80°C. or higher and, thereafter, recovering an odor-improved and storage-stable olefinic derivative.

11 Claims, No Drawings

**PROCESS FOR THE ODOR REMOVAL OF
MALODOROUS SULFUR CONTAINING OLEFINIC
DERIVATIVES**

The present invention relates to a novel process for upgrading sulfur-contaminated olefinic derivatives. More particularly, it relates to a process for upgrading malodorous sulfur-contaminated aliphatic, aromatic or cycloaliphatic olefinic derivatives and mixtures thereof by substantially removing the offensive odor therefrom. Still more particularly, the invention is concerned with a method for treating said sulfur-contaminated olefinic derivatives or mixtures thereof with an organic peracid defined hereinbelow with particularity in an amount sufficient to obtain storage-stable, odor improved olefinic derivatives.

In the past, attempts have been made to upgrade malodorous olefinic derivatives such as sulfate turpentine distillates. Unfortunately, none has been wholly successful. One method, for instance, has been to subject malodorous sulfate turpentine to steam distillation. This removes low boiling sulfur contaminants. Since some of the sulfur impurities which are naturally present have boiling points similar to that of the terpene components, separation of these impurities presents obvious difficulties. Another method has been to treat sulfate turpentine distillates with an aqueous hypochlorite solution to "sweeten" its odor by oxidizing the sulfur compounds contained therein. Though the odor is somewhat improved, the use of hypochlorite introduces undesirable chlorine in the form of organic chlorides. The latter are both malodorous and corrosive and the use of hypochlorite can lead to adverse physiological side effects. Consequently, these methods have not been met with universal acceptance. If a process could be developed which obviates the difficulties of the prior practice, such would meet a need long sought after in the art.

It is, therefore, a principal object of the invention to minimize offensive odors generally attributable to sulfur-contaminated olefinic derivatives. It is a further object to provide a relatively simple, economical and effective method for reducing offensive odors in olefinic derivatives having associated therewith sulfur-containing impurities, such as mono and disulfides. Other objects and advantages will become apparent to one skilled in the art from a reading of the ensuing description.

To this end, there is provided a relatively straightforward, simple and effective method for attaining a marked improvement in malodorous aliphatic, aromatic or cycloaliphatic olefinic derivatives or mixtures thereof. Unexpectedly, the improvement is attained by admixing small amounts of an organic peracid with the latter olefinic derivatives without adversely affecting said olefinic derivative by rearrangement, epoxidation and the like. Such admixture can take place over a wide range of temperature, usually from about minus (-) 10°C. to about 80°C. or higher. Surprisingly, the odor of the so-treated olefinic derivative is markedly improved and remains storage-stable with respect to odor over a prolonged period of time, whereas the olefinic derivative remains unaffected notwithstanding the known conversion of olefins to epoxides in the presence of peracids.

According to the process of the invention, any commercially available sulfur-contaminated olefinic deriva-

tive or mixture thereof can be subjected to the action of an organic peracid over a temperature ranging from -10°C. to 80°C. or higher up to the decomposition point of the peracid. In general, the addition of from about one equivalent to not more than two equivalents of an organic peracid per mole of sulfur in said olefinic derivative is sufficient to oxidize the sulfur content therein, thereby reducing any offensive odor therein to a highly commercially acceptable level.

10 Any of a plurality of sulfur-contaminated olefinic derivatives usually containing more than 100 parts per million (ppm.) of sulfur present as an organic divalent sulfur species, can be treated in accordance with the process of the invention. Illustrative of these are: sul-

15 fate turpentine, sulfate pine oil, dipentene, anethole, sulfur-contaminated gasoline, sulfur-contaminated pentane, and equivalents thereof. Advantageously, any branched, unbranched, or cyclic olefinic derivative may be employed in the process of the invention.

20 Exemplary peracids, which are characterized as being at least slightly soluble in the olefinic derivatives to be treated, are: performic acid, peracetic acid, perpropionic acid, perbutyric acid, perpentanoic acid and equivalents of the same, usually present from a 10 to 50 percent solution, by weight, in aqueous parent acid solution. Such per(lower)-alkanoic acids as well as their method for preparation are well known in the art. Generally, as above stated, from one to two equivalents of said peracid per mole of sulfur in said olefinic derivative is sufficient to oxidize the sulfur content. A good operating amount of peracid based on 200 to 5,000 ppm. sulfur usually ranges from about 0.1 to about 5.0 percent, and preferably from 0.5 to 2 percent, all by weight of said organic peracid. Such amount of per-

25 acid, when added to a sulfur contaminated olefinic derivative is sufficient to reduce offensive odors therein to a highly commercially acceptable level. Of course, such amount is dependent upon the overall sulfur content. However, the utilization of an amount in excess of 30 5 percent of the peracid when not required to oxidize sulfur is not preferred for the reason that the cost is increased and little, if any, additional advantage either by way of increasing the level or extending the period of odor control is attained.

35 40 45 It is an advantage of the process herein to effect the selective oxidation of sulfur impurities by converting the same to substantially less noxious impurities without affecting the unsaturated bonds of the olefinic derivative so-treated. Further, there is no need for specialized equipment to carry out the process of the invention. Rather, the present process utilizes inexpensive equipment operable over a wide range of temperatures. Deodorization is attained upon the addition of

50 55 60 the peracid within a relatively short period of time, usually from about one second to 10 minutes after addition commences, although longer residence time ranging from one to three hours can be used for manufacturing convenience without any deleterious effect.

In order to facilitate a further understanding of the invention, the following examples are given primarily for purposes of illustrating certain more specific details thereof. The scope of the invention is not to be deemed limited thereby except as defined by the instant claims. Unless, otherwise noted, the parts are by weight.

EXAMPLE 1

A suitable flask immersed in a water bath at 20°C.

and equipped with stirrer and a thermometer is charged with 500 parts of sulfate pine oil containing 5,200 ppm. of sulfur. Stirring is initiated and 19.3 parts of 40% peracetic acid are slowly added at a rate so as not to exceed a pot temperature of 30°C. Temperature is controlled by means of the cooling bath. The total time of addition is 15 minutes.

Resultant reaction mixture is stirred at ambient temperature for an additional 45 minutes. It is then washed with water and then followed by an aqueous sodium carbonate solution wash to obtain an odor improved product. Subsequent steam distillation affords 465 parts of a distillate whose odor characteristics are markedly improved over those of the starting-pine oil. On analysis, it is found that the sulfur content had been reduced to 319 ppm.

Similar results are obtained when utilizing performic or perpropionic acid in lieu of peracetic acid in the above-stated procedure.

EXAMPLE 2

A suitable flask equipped with a magnetic stirring bar is charged with (a) 100 parts of anethole containing 160 ppm. of sulfur and (b) 1.0 part of 40% aqueous peracetic acid. Resultant mixture is stirred for one hour and then washed with water and subsequently steam distilled, employing the procedure of Example 1 above, to yield 93 parts of organic distillate of significantly improved odor. On analysis, the distillate exhibited a sulfur content of 20 ppm.

Substituting perbutyric acid for the peracetic acid above and sulfur contaminated β -pinene for anethole, similar results are obtained.

EXAMPLE 3

A suitable flask, immersed in a water bath and equipped with a stirrer and a thermometer is charged with 100 parts of a particularly foul smelling crude sulfate turpentine containing 4,800 ppm. of sulfur. Stirring is initiated and 7.0 parts of 40% aqueous peracetic acid are slowly added at a rate so as not to exceed a pot temperature of 25°C.

Subsequent to the addition of all the peracid, the resulting mixture is stirred at ambient temperature for one hour and is then washed with water to obtain an odor improved product containing 200 ppm. sulfur. It is next steam distilled as set forth in Example 1, to yield 93 parts of a pleasant smelling distillate which is found to contain 95 ppm. of sulfur.

EXAMPLE 4

Substituting a foul smelling, sulfur-contaminated gasoline for the crude sulfate turpentine of Example 3 above, there is employed the procedure of said Example 3 in every detail. A "sweet" smelling gasoline is obtained of substantially reduced sulfur content.

EXAMPLE 5

A 100 g. sample of malodorous cyclohexene, containing 5,000 ppm. sulfur present as n-butyl ethyl sulfide, is cooled to 15°C. and 4.0 g. of 40% (by weight) peracetic acid is slowly added at a rate so as not to exceed a pot temperature of 25°C.

After the peracid treatment is completed, the resulting mixture is stirred briefly at ambient temperature and is washed successively with 2 $\times$ 100 ml. portions of deionized H_2O , 50 ml. of 5% Na_2CO_3 and finally, an additional 100 ml. of deionized H_2O .

The washed material is then steam distilled to yield 90 g. of a pleasant smelling distillate which is found to contain 35 ppm. of sulfur.

I claim:

1. A method for the upgrading of a malodorous, sulfur-contaminated aliphatic, aromatic, or cyclic olefinic derivative or mixture thereof which comprises the steps of: contacting said malodorous sulfur-contaminated olefinic derivative or mixture thereof with between about 0.1 and about 5.0 percent, by weight, of a per(lower)alkanoic acid, at a temperature ranging from minus(–) 10°C. to 80°C., water washing the so-treated olefinic derivative, and thereafter recovering an odor-improved, storage-stable, sulfur-reduced olefin.

2. The method according to claim 1 wherein there is employed from one to two equivalents of the per(lower) alkanoic acid per mole of sulfur in said olefinic derivative.

3. The method according to claim 2 wherein the so-washed treated olefinic derivative is further subjected to distillation prior to recovering the same.

4. The method according to claim 2 wherein the per(lower)alkanoic acid is selected from the group consisting of peracetic, perpropionic, perbutyric and perpentanoic acids.

5. The method according to claim 2 wherein the per(lower)alkanoic acid is peracetic acid.

6. The process according to claim 2 wherein the per(lower)alkanoic acid is perpropionic acid.

7. The process according to claim 2 wherein the olefinic derivative to be treated is crude sulfate turpentine.

8. The process according to claim 2 wherein the olefinic derivative to be treated is crude sulfate pine oil.

9. The process according to claim 2 wherein the olefinic derivative to be treated is sulfur-contaminated anethole.

10. The process according to claim 2 wherein the olefinic derivative to be treated is sulfur-contaminated gasoline.

11. The process according to claim 1 wherein the per(lower)alkanoic acid is present in an amount ranging from 0.5 to 2.0 percent, by weight.
